UNITED STATES PATENT OFFICE.

FRANK S. HAWKINS, OF WORCESTER, MASSACHUSETTS.

POWER MOLDING-MACHINE.

SPECIFICATION forming part of Letters Patent No. 270,898, dated January 23, 1883.

Application filed June 16, 1882. (No model.)

To all whom it may concern:

Be it known that I, FRANK S. HAWKINS, of the city and county of Worcester, and Commonwealth of Massachusetts, have invented 5 certain new and useful Improvements in Power Molding-Machines; and I do hereby declare that the following is a full, clear, and exact description of the same, reference being had to the accompanying drawings, forming a part 10 of this specification, and in which—

Figure 1 represents a top or plan view of my aforesaid improved power molding-machine. Fig. 2 represents a side view of the machine shown in Fig. 1, looking in the direction indicated by arrow *a*, same figure. Fig. 3 represents a vertical section through the machine, taken on line A A, Fig. 1, looking in the direction of arrow *a*, same figure. Fig. 4 represents a vertical section through a part 20 of the machine, taken on line B A, Fig. 1, looking in the direction of arrow *a*, same figure. Fig. 5 represents a vertical section on line D D, Fig. 4, looking in the direction of arrow *c*, same figure. Fig. 6 represents a top or plan view of a part of the machine, which will be hereinafter more fully described, and Fig. 7 represents a front end view of the parts shown in Fig. 6, looking in the direction of arrows *d*, Figs. 1, 2, and 6. Figs. 8, 9, and 10 are 25 detail views of certain parts.

My invention relates to a machine for that class of molding in sand called "snap-flask" molding.

It consists in constructing and arranging 35 the several parts of the machine so that by operating a hand-lever pressure may be applied to or withdrawn from the sand at will by steam or other power properly connected with said machine.

40 It also consists in the combination of a "sprue-hole" cutting or punching device with the aforesaid pressure mechanism, whereby the sprue-hole is automatically punched in the sand at the proper time, as will be hereinafter more fully explained.

To enable those skilled in the art to which my invention belongs to make and use the same, I will proceed to describe it more in detail.

45 In the drawings, E E represent two side frames for supporting the several parts of the machine.

F represents the main driving-pulley, which may be connected by means of a belt with any suitable driving mechanism. Said pulley 55 is fitted to turn upon horizontal shaft G, which in turn is fitted to turn in suitable bearings H H'. (See Figs. 1 and 2.) Upon shaft G are also arranged a clutch, I, and disk J. The former is arranged to slide longitudinally, 60 but prevented from turning upon the shaft by means of a spline, f, fitted into both of said parts, and the latter (disk J) is keyed or otherwise rigidly fastened, so as to turn with the shaft when operated. Clutch I is 65 clutched and unclutched to and from the notched hub F' of driving-pulley F by means of a hand-lever, K, which is hinged to a bearing, g, formed upon or secured to a cross-frame piece, L, fastened at each end to the side 70 frames, E E. The outer end of lever K is provided with an operating-handle, K', and its inner upper end is hinged to a link-piece, K², which link-piece is in turn hinged to the end of an angular forked shipping-lever, K³, hinged 75 at h to a supporting part, k, extending up from cross-frame piece L. The other forked end of said shipping-lever K³ is arranged in the circular groove l, formed on the clutch I. Thus by this arrangement it will be seen that by depressing the handle K' of lever K the clutch is engaged with the notched hub F' of the driving-pulley, and held there by the tilting piece m until released by the pin n, as herein-after described.

85 The clutch I is held in position against the notched hub F' while the machine is in operation by means of tilting part m, pivoted near the center upon a pin, m³, pointed at one end, m', and made heavier at the other end, m². Said 90 part m is supported on bearings m⁴ m⁴, formed on frame-piece m⁵, which frame-piece forms a branch of cross-frame piece L, and is extended up to form the support and bearing H' for shaft G. In this instance said frame-piece m⁵ 95 is fastened to a part, k, extended up from part L; but, if preferred, they may be formed in one piece. When the clutch I is in action with the hub F' of the driving-pulley the locking-pin m occupies a horizontal position, as represented in Figs. 1, 3, and 4, with its upper side (at the pointed end m') bearing against the frame-piece m⁵ at the upper end of a slot, m⁶, (see Figs. 3 and 4,) formed in said frame-piece.

Said slot m^6 is extended down a sufficient distance and the pointed end made of sufficient length to allow the locking-pin m to be tilted enough to admit of the clutch being disengaged from its driving-hub. The locking-pin m is tilted, as aforesaid, by means of a pin, n , which is fastened upon the inner side of the disk J , said pin being so arranged and timed, in connection with the shipping mechanism, 5 that it will depress the pointed end m' of the tilting part m and allow the clutch to unship when the compressing-plate Q is in its highest position. When the clutch is unshipped the operating-lever K is forced up, so as to swing 10 the upper end back, by means of a spiral spring, K^4 . At the same time that the driving-power is unshipped the disk J is stopped and held by a brake, K^5 , formed upon the end of a lever, K^6 , which projects laterally from lever 15 K , being held by and arranged to turn in a suitable bearing, K^7 , at its outer end.

The parts marked M represent a metal grating, upon which is first placed a "match-board" and then the pattern. The lower "half-flask" or "nowel" is next placed in position upon the match-board and filled with sand. A "bottom board," N' , (having cleats M' fastened to it,) the size of the inside of the nowel, is then placed over all, with the cleats on top, 20 and the machine started by depressing the hand-lever K , which operation brings the compressing-plate Q down upon the cleats M' of the bottom board N' , and compresses the sand. The machine, now continuing to operate, is automatically stopped at the end of one revolution of disk J , as elsewhere described, leaving 25 the compressing-plate in its elevated position. The nowel is now removed by hand, and the match-board then removed, which leaves the pattern O at the top embedded in the sand, as 30 shown in Fig. 3 of the drawings.

Up to this point in the molding operation (except the manner of compressing the sand, as hereinafter described) the method is the 35 same or similar to that usually employed, and I therefore make no claim thereto, except in combination with my improvements. Neither do I make any claim, in a broad sense, to a power molding-machine, as I am aware that 40 there are several already patented, but of different construction from mine.

After the lower half-flask or nowel has been inverted, as before described, and the "parting" or dry sand sprinkled over the same 45 to prevent adhesion, the upper half-flask or "cope," P , is then arranged directly over said nowel and filled with sand. The upper half-flask or cope having been filled with sand, as aforesaid, the compressing-plate Q is now 50 again made to descend and compress said sand in a proper manner. At the instant when the compressing-plate Q is at its lowest position a sprue-hole cutting or punching device is brought into action by the same operation of 55 the hand-lever K , which operation not only punches the sprue-hole, but also releases the spring y^2 (see Fig. 6) and allows the levers $S S'$

to engage in slots $q^2 q^3$ in the cope, thereby raising said cope with the compressing-plate. The pattern is now drawn out of the sand in 70 the nowel and the machine started, which operation lowers the cope and sand in the same together and leaves them in the position shown by full lines in the drawings, the compressing-plate rising into its elevated position after 75 leaving the cope and sand, as aforesaid. The cope may now be unfastened and swung back, when the molding operation is completed.

The compressing-plate Q and sprue-hole-punching device are constructed, arranged, 80 and operate in the following manner:

The compressing-plate Q is fastened upon its upper side to two arms or levers, $Q' Q'$, which are hinged upon a horizontal shaft, R , fastened at each end to the side frames, $E E$. 85 Said plate is raised and lowered by the operation of disk J , (which turns in the direction shown by arrows e .) being connected with said disk by means of link-sections $R', R^2 R^2$, and $R^3 R^3$, one end of the section R' being hinged to the disk near its periphery, its other end hinged to the lower ends of sections $R^2 R^2$ and upper ends of sections $R^3 R^3$, the sections R^2 90 hinged at their upper ends to a strong cross-piece, R^4 , fastened at each end to the side frames, $E E$, and the lower ends of the sections R^3 hinged to the plate-holding arms $Q' Q'$. By this construction it will be seen that the greatest pressure, which is a very strong one, is produced, when it is most needed, after 95 the plate has been nearly lowered and commences to press upon the sand.

During the operation of compressing the sand in the lower half-flask or nowel, the upper half-flask or cope is swung around (as 100 before stated, and shown by dotted lines in Fig. 1) out of the way, being hinged at the back corners, $o o$, and fastened at the center in front by a latch device, p , to admit of this adjustment. The cope is provided with flanges $P' P'$, which extend back to form bearings for 105 it to swing upon the shaft R . After the sand in the cope has been compressed, said cope and the compressing-plate Q are locked together, so that the cope containing the compressed 110 sand may be raised to remove the pattern O by springing the outer ends, $q' q'$, of the levers $S S'$ into the slots $q^2 q^3$, formed in the ears or flanges $q^3 q^3$ at each side of the cope. (See 115 Figs. 1, 2, 6, and 7 of the drawings.)

In Fig. 1 the locking latches or levers $S S'$ are represented as being locked into the slots $q^2 q^3$ by full lines, and by dotted lines as being disengaged or drawn out of the same. Said locking and unlocking operation is performed in the following manner: The inner 120 end of the lever S' is notched onto the end of the other lever, S , as is shown in Figs. 1 and 6, so that when said lever S' is drawn forward from its inner end both levers will be 125 operated alike. If preferred, any other similar method may be employed. The outer ends of the locking-levers are kept sprung out, as shown by full lines, except when forced back,

by means of springs r r , fastened to the outer sides of the holding-arms Q Q' . They are forced back, so as to unlock the plate from the cope, by means of a lever, S^2 , which is hinged 5 at s to the inner end of the lever S' . Said lever S^2 is guided and held in position laterally by means of guides t t' , fastened to the upper side of the compressing-plate Q , and is drawn forward at the proper time by means of a hook, u , catching in the notched end S^3 of said lever S^2 . Hook u is hinged to the lower end of a vertically-arranged swinging lever, T , which is fulcrumed to a bearing, T' , on cross-frame L , and said lever T , which in this instance is angular in shape, (see Fig. 5,) is provided at its upper end with a pointed head or cam part, T^2 , which, as the disk J revolves, is struck by a cam-pin, v , which forces the upper end of the lever back into the position shown in Figs. 3 10 and 4 of the drawings, and thereby causes the locking-levers S S' to be drawn out of the slots q^2 q^2 into the positions shown by dotted lines in Fig. 1, thus releasing the cope from the compressing-plate Q . The locking-levers S S' , 15 when drawn out of the slots q^2 q^2 , as before described, are held in that position by spring y^2 engaging in a notch in the under side of the pulling bar or lever S^2 .

The sprue-hole-punching device consists of 20 a swinging lever, U , which is hinged at one end upon the horizontal shaft R , and is provided at the other end with a hollow sprue cutter or puncher, V , which is adjusted to strike through the sprue-hole w^2 in the compressing-plate. In this instance said sprue-cutter is provided with a funnel-shaped opening, w , and projecting part w' , which strikes in the opening w^2 of the compressing-plate, when it is swung down. The swinging lever 25 U is kept in an elevated position, when not in use, by means of a spiral spring, x , arranged over the shaft R , one end being fastened to said shaft, while the other end is fastened to the lever. Any other similar device suitable 30 for the purpose may be employed. Said lever U is operated to cut the sprue-hole by means of a hook, y , hinged to lever T , by said hook engaging in a catch or notch formed in the hinged pull bar or lever W , one end of the bar 35 or lever W being hinged to the sprue-lever U and the other end loosely supported and guided in a loop, y' , fastened to the lower end of lever T . Lever W , being hinged to the sprue-holding lever U , close to the bearing of the 40 same, causes said lever to be swung over to punch the sprue-hole by a quick movement.

The pull-bar S^2 is unlocked, so as to allow the levers S S' to be sprung forward into the slots q^2 q^2 by springs r r , by the sprue-lever 45 U striking the spring y^2 and forcing it down out of the notch in the under side of the bar, when said lever is swung down to cut the sprue-hole.

The hooks u and y are raised and lowered 50 so as to engage with or disengage from the notches on draw-bar S^2 and lever W , as required, by means of rods X X' , angular plate X^2 , fulcrumed to swinging lever T near its

bearing, rod X^3 , angular plate X^4 , fulcrumed to the under side of the inner end of hand-lever K , rod X^5 , angular plate X^6 , fulcrumed 70 to the side of the hand-lever near its handle K' , and operating-levers Y Y' , which are operated, in conjunction with hand-lever K , by forcing them toward or from the handle K' , as the case may be—as, for instance, if it is required to raise hook u out of the way and depress hook y , the lever Y' would be forced toward the handle K' , as shown in the drawings, and vice versa for lowering hook u .

The part marked Z represents simply a brace 80 to strengthen frame-piece m^5 , which supports one end of shaft G .

Supposing the compressing-plate Q to be in an elevated position, the lower half-flask or nowel as having been reversed in the operation of forming a mold, as before described, the parting sand sprinkled over the same, and the upper half-flask or cope unfastened and the two halves swung out apart, as shown by dotted lines in Fig. 1. The operation of completing the mold by the use of my machine may be briefly summed up thus: Said cope P is first swung into position and fastened and filled with sand, when the hand-lever K is then depressed, thereby causing the compressing-plate 90 to be lowered and the sand thereby compressed, and at the same time the sprue-hole-punching device is operated, as before described, and the sprue-hole punched in the sand, which at the same time locks the compressing-plate 100 to the cope by the sprue-hole-punching lever striking the spring y^2 , when it descends, and thus releasing the locking-levers, so that they will spring forward into the slots in the ears or flanges q^3 q^3 of the cope P . The plate Q and 105 cope containing the compressed sand are then raised together into a nearly vertical position by the continued rotation of disk J . The power is then automatically unshipped and the pattern removed or drawn out, as before described. The hand-lever is now depressed a third time and the lever Y (see Fig. 3) also forced toward handle K' , which operation lowers the compressing-plate and cope, and at the same time releases said cope from the plate by 110 the lever S^2 being drawn back by hook u , as before described, and by the continued rotation of disk J the compressing-plate is again raised into its original elevated position. The cope is now unfastened and swung back into 120 the position shown by dotted lines in Fig. 1, and the nowel removed preparatory to forming the next mold.

Having described my improvements in power molding-machines, what I claim there- 125 in as new and of my invention, and desire to secure by Letters Patent, is—

1. The combination of the lower half-flask or nowel, N , and the upper half-flask or cope, P , of a power molding-machine with compressing-plate Q , hinged holding-arms Q Q' , link-sections R^3 R^3 , R^2 R^2 , and R' , cross-frame piece R^4 , and the revolving disk J , substantially as and for the purpose set forth.

2. The combination of disk J, link-sections R', R² R², R³ R³, compressing-plate Q, cope P, nowel N, hinged arms Q' Q', horizontal shaft R, and side frames, E E, substantially as shown and described, for the purpose stated.
3. The combination of the cope P, having bearings P' P', hinged corners o o, and fastened at one side by means of a fastening device, p, with horizontal shaft R, substantially as and for the purpose set forth.
4. The combination, with the cope P and compressing-plate Q, having a sprue-hole, w², near the center of the same, of hollow sprue V, its holding-lever U, shaft R, spring x, notched pull bar or lever W, hook y, swinging lever T, provided with pointed head T², bearing T', cross-piece L, side frames, E E, pin v, and disk J, substantially as and for the purpose set forth.
5. The combination, with the cope P, having slotted ears or flanges q³ q³, of locking-levers S S', compressing-plate Q, plate-holding arms Q' Q', springs r r, notched pull bar or lever S², guides t t', spring y², and sprue-holding lever U, substantially as and for the purpose set forth.
6. The combination, with notched pull bar or lever S², of hook u, swinging lever T, provided with a pointed head, T², bearing T', cross-piece L, pin v, and revolving disk J, substantially as and for the purpose set forth.
7. The combination, with hooks u and y, of rods X X', turning angular plate X², swinging lever T, rod X³, turning angular plate X⁴, hand-lever K, rod X⁵, turning angular plate X⁶, and operating-handles Y and Y', arranged on opposite sides of the handle K', of lever K, substantially as and for the purposes set forth.
8. The combination, with the hub F', of driving-pulley F, shaft G, and spline f, of clutch I, having a circular groove, l, angular forked lever K³, cross-piece L, supporting part k, link or connecting rod K², hand-lever K, (provided with handle K'), and bearing g, substantially as and for the purpose set forth.
9. The combination, with angular forked lever K³, of tilting part m, pointed at the end m' and made heavier at the other end, m², tilting pin n, disk J, pivot-pin m³, bearings m⁴ m⁴, angular supporting part m⁵, slotted at m⁶, shaft G, and part k, substantially as and for the purpose set forth.
10. The combination of the cope P and nowel N, hinged arms Q' Q', link-sections R³ R³, R² R², R', disk J, shaft G, bearings H H', their supports, and driving-pulley F, provided with notched hub F', clutch I, and its shipping-lever K³, substantially as shown and described, for the purpose stated.
